SANITARY PACK UNIT

William V. Rea and Pamela F. Rea,
Calumet City, Ill.Application October 10, 1933, Serial No. 693,014
Renewed April 13, 1936

7 Claims. (Cl. 206—57)

Our invention relates to improvements in sanitary pack units and it more especially consists of the features pointed out in the claims.

The purpose of our invention is to provide a self-contained pack of sanitary toilet seat covers, which includes, a support or backing to which the sheets of paper are attached at its lower edge, and that has a band or forward support at its upper edge in front of the assembled sheet. This prevents the upper or folded portion of the sanitary sheets from falling forward as a single sheet is withdrawn; all of which constitutes a complete unit. It is also a purpose of our invention to support the entire weight of the pack unit on a pair of standards attached under the hinge bolts of a toilet seat; that provides openings at the bottom edge of the pack for the introduction of the standards; that by reason of these features our invention may entirely dispense with a conventional cabinet; and that if desired we may also use the same pack unit when placed in any form of container without any change in the structure of the unit.

This application is a continuation in part of our application Serial No. 562,313 filed September 11, 1931, which matured into Patent No. 1,934,326 on November 7, 1933.

With these and other ends in view we illustrate in the accompanying drawing such instances of adaptation as will disclose the broad underlying features of the invention without limiting ourselves to the specific details shown thereon and described herein.

Fig. 1 is a semi-perspective view of the three forms of backing A, B, and C combined with a front support at the top to prevent assembled sheets from falling forward.

Fig. 2 is a front elevation of a complete unit. Fig. 3 is an enlarged side elevation in section 40 on line 2—2 of Fig. 2.

Fig. 4 is a plan view of an unfolded single sheet.

Fig. 5 is an enlarged elevation of the bottom edge of a pack.

Fig. 6 is a diagrammatic elevation instancing 45 four kinds of folds of the paper sheets.

In utilizing our invention we may use whatever alternatives or equivalents of parts that the exigencies of varying conditions may demand without departing from the broad spirit of the invention.

We believe that our instant invention is the first in the history of the art that provides a self-contained sanitary pack unit that can be used entirely independent of a cabinet or container, 55 and when all the sheets of a unit have been re-

moved the entire backing can be discarded and a new unit substituted, hence we claim the unit in its broadest scope.

The pack unit comprises a group of sheets 9 assembled together. They are held onto a stiffened backing 11 by means of any desired fastenings 12 at the narrow lower end. These fastenings pass through a narrow reinforcing strip 8. The upper portion of the pack may be provided with a permanent band or support 13 forming an 10 integral part of the backing 11 (Fig. 1A) or a separate band 13 may be attached to the back (Fig. 1B) or the back may be continued over the top and pass downward to form a front support 10 (Fig. 1C). These supports serve to hold even 15 a single sheet from dropping down when not wanted. If desired the sheets of a pack may be additionally held by the fastenings 6 (Fig. 1C) which hold the lower edge of the forward support 20 from moving away from the backing.

The assembled sheets due to their being folded at or near the line 17 on Fig. 4 present a greater thickness of the pack at 26 the top than at the thinner portion 15 at the bottom. There is a pull-out portion of each sheet, indicated at 18. Various kinds of folds 17 are shown at A, B, C and D of Fig. 6. The pullout portion 18 projects from beneath the front downward extension 10 of the backing 11. This portion 10 yieldably serves the same purpose as the bands 10 and 13 shown in 30 Figs. 3 and 4 of our copending application Serial No. 562,313.

When the pack is used as a self-contained unit independently of a container the forward fold or bend on its underside, at 7, rests on the upper 35 ends 27 of the metal standards 19 whereon the entire weight of the pack is supported. By eliminating the necessity of having a cabinet or container we are enabled to produce a pack unit occupying a very small space in front of the usual 40 flushing tank.

The standards 19 are provided at their lower ends with forwardly projecting feet 20, that have openings through which the usual fastening bolts for the hinges 24 of the cover 23 pass. Nuts 22 45 hold the feet and the hinges in place on the bowl 25. The standards 19 impart rigidity to the entire assembly. In order that they may be easily inserted into the openings 1, at the bottom of the pack, Fig. 5, the backing 11 has secured 50 fillers 2 between it and an inner reinforcement 4 to the front of which the last sheet 3 of the pack is attached, so that the standards 19 will readily pass between such sheet and the backing 11 without tearing the sheet. If desired the strip 55

4, of paste board, may be extended some distance up from the bottom edge of the pack. The sheets 9 and the front support may be fastened at 6 to the backing 11 or the fastenings 6 (not shown) may be outside of the side edges of the sheets 9 to form a guide in which event any filler expedient may if needed be used to slightly separate the lower edge of the front from the backing 11 to form a space for the folded portion 10 of the sheets.

5 The individual sheets 9 may be folded as shown in Fig. 6, in any event they will have a protective central portion 14 detached, except at 16. It is of course immaterial as to the grade of paper or 15 the kind of material that is used for the backing. The entire unit can be produced economically and there is no complexity in installing or manipulating the pack.

20 The fastenings 6 hold the sheets of the pack 9, the backing 11 and the front 10 together as shown in Figure 2 and it is obvious that if the sheets 9 were made narrower than the space between the fastenings 6 in Figure 2 such fastenings would be outside of the edges of the sheets 25 in which event the front 10 and the backing 6 with any kind of a narrow filler between to make up the extra thickness at the point where the sheets are folded would serve the same purpose in holding the front 10 in a certain spaced apart 30 relation to the backing 11, so as to accommodate the extra thickness of the folded sheets or if the fastenings 6 for the front 10 and the backing 11 were more or less loose the sheets 9 would not be clamped tightly between the front and the backing 35 and thus the free removal of the sheets 9 would not be interfered with.

What we claim is:—

1. A sanitary pack unit comprising a backing 40 extending the full length of the pack which is bent forward and downward at its upper end, a plurality of sanitary sheets placed against the backing and secured thereon at their lower edges, and means for holding the lower edge of the bent over portion free to swing forward independently 45 of the backing.

2. A sanitary pack unit comprising a backing 50 extending the full length of the pack having a forward and a downward projection at its upper end, and a plurality of sanitary sheets attached to the backing at a plurality of points including their lower ends said sheets being folded beneath the forward projection of the backing and having a pullout portion projecting from below the downward extension of the backing.

55 3. In sanitary pack units, a discardable backing extending the full length of the pack having a plurality of sanitary sheets attached to the

backing at its lower edge, an extension from the top of the backing projecting forward to provide storage space for the upper folded edge of the sanitary sheets, a downward extension from said projection adapted to hold the upper edges of the assembled sheets against displacement while a single sheet is being withdrawn from the pack, and means comprising an encircling band for maintaining the downward projection in yielding relation to the backing.

4. A sanitary pack unit comprising a plurality of folded sanitary sheets, a suitable backing extending the full length of the pack, means at the lower end for fastening the sheets, a lateral projection from the backing at its upper edge which 15 projection extends downward in front of the folded portion of the sheets, and reinforcing means associated with the fastening means used at the lower end of the backing and the sheets said means providing a free entrance from the 20 exterior of the pack leading to the interior in front of the backing and to the rear of the first assembled sanitary sheet by raising the downward extension.

5. A sanitary pack unit including a discardable 25 backing extending the full length of the pack, a plurality of sanitary sheets folded along their top edge, means comprising a forward and downwardly projecting extension of the upper edge of the backing adapted to hold the loosely assembled sheets at their folded upper edges from falling down when a single sheet is being detached from the pack without using fastenings passing through the sheets, a separate band encircling the upper end of the backing and its 30 downward projection, and means for securing the unfolded portion of the sheets to the backing at its 35 lower edge.

6. A sanitary pack unit comprising a backing, a plurality of sanitary sheets attached to said backing, and means associated with the upper portion of the backing arranged to hold the assembled sheets near their upper portion from falling down when the pack is in use in its upright position, said means consisting of portions extending forward from the backing and around the edges of the sheet pack.

7. A sanitary pack unit comprising a backing, a plurality of sanitary sheets attached to said backing, and means associated with the upper portion of the backing arranged to hold the assembled sheets near their upper portion from falling down when the pack is in use when it is in its upright position, said means consisting of a band 50 surrounding the sheet pack.
